UNITED STATES PATENT OFFICE.

JOSEPH MASON AND WILLIAM J. BEATTIE, OF FITCHBURG, MASSACHUSETTS,
ASSIGNORS TO PYRO-PIN MANUFACTURING COMPANY, OF FITCHBURG, MASSACHUSETTS.

GAME APPARATUS.

1,163,432.

Specification of Letters Patent.

Patented Dec. 7, 1915.

Application filed June 7, 1915. Serial No. 32,617.

To all whom it may concern:

Be it known that we, JOSEPH MASON and WILLIAM J. BEATTIE, citizens of the United States, residing at Fitchburg, in the county 5 of Worcester and State of Massachusetts, have invented certain new and useful Improvements in Game Apparatus; and we do declare the following to be a full, clear, and exact description of the invention, such as 10 will enable others skilled in the art to which it appertains to make and use the same.

This invention relates to improvements in game apparatus.

One object of the invention is to provide 15 simple and efficient means wherein a pool or billiard table may be instantly adapted for use in connection with a game having the attributes and fascinations of duck or ten pins.

Another and further object is to provide 20 a means for locking an angular cushion bearing frame adjacent one end of a pool or billiard table.

Another and still further object is to provide 25 vide a unique and expeditious means for permanently maintaining the respective sections of the angular cushioning member in fixed relation.

Another and still further object is to design 30 a cushioning member which, when operatively disposed, will have the cushions thereof form a continuation of those on the table upon which it is mounted.

With these and other objects in view the 35 invention consists of certain novel features of construction and the combination and arrangement of parts hereinafter referred to and more particularly pointed out in the claims.

In the accompanying drawings in which 40 corresponding parts are indicated by similar reference characters: Figure 1 is a plan view of a billiard table showing our improved game apparatus applied thereto; 45 Fig. 2 is a vertical transverse section, taken on line 2—2 of Fig. 1; Fig. 3 is a detail vertical section on line 3—3 of Fig. 1; Fig. 4 is a fragmentary top plan view of the angular, cushioned frame; Fig. 5 is a bottom view 50 thereof; Figs. 6 and 7 are detail transverse sections, taken respectively on lines 6—6 and 7—7 of Fig. 4; Fig. 8 is a detail horizontal section on line 8—8 of Fig. 6; Fig.

9 is a horizontal section on line 9—9 of Fig. 2, showing more particularly the arrangement of the locking pins; Fig. 10 is a detail perspective view, showing one of the locking pins.

Briefly stated, our invention consists of an angular cushioned frame adapted to be 60 positioned at one end of a standard pool or billiard table with its vertex coincident with the longitudinal axis of the latter. When this frame is positioned as aforesaid, a plurality of miniature ten pins are arranged in 65 the usual ten pin order adjacent one of its legs so that when a rolling object is projected against the other leg thereof it will be deflected to the adjacent leg and rebounding from the latter will strike more 70 or less of the pins, dependent on the accuracy with which the rolling member is projected.

Referring more particularly to the accompanying drawings, A indicates the bed 75 of a standard billiard table, B its supporting legs, C the side banks, and D the head banks. A pair of strips or legs 1 and 2 respectively, formed of wood or other suitable material, have their inner extremities 80 3 beveled so that when the latter are brought into contiguous relation their beveled surfaces will miter, and the respective legs be positioned at right angles to form an angular frame 2', as clearly shown in 85 Fig. 1 of the drawings. The outer extremities 4 of the respective legs 1 and 2 abut the side banks C (see Figs. 2 and 9) and are held in position, as hereafter described.

To fixedly and firmly secure the legs of the 90 frame 2' in angular relation a right angular tie plate 6 is secured to the upper surfaces of the legs 1 and 2 contiguous to the mitering ends thereof. This tie plate 6, which has its vertex coinciding with that of the angle 95 formed by the legs of the frame 2' is provided with suitable countersunk openings 7 which register with the openings formed in the legs for the passage of suitable fastening elements 8.

Formed in each of the legs of the frame 2' adjacent the extremities 3 thereof is a longitudinally extending recess 9. These recesses 9, when the respective legs are disposed in right angular relation, form a right 105 angular shaped seat which is adapted to re-

ceive a similarly designed tie plate 10, the latter having countersunk openings 11 adapted to receive suitable fastening elements 12. By arranging the tie plate in the manner aforesaid, it will be obvious that the legs 1 and 2 of the frame 2' will be firmly and securely bound in right angular relation.

To positively eliminate any lateral movement on the part of the respective legs of the frame, a metallic anchoring piece 13 having the right angularly disposed integrally formed apertured wings 14, is employed. This metallic piece, when the legs 1 and 2 of the frame are operatively disposed, is positioned upon the frame 2' at a point coincident with the point of intersection of the two legs thereof, the wings of said metallic anchor overlying the contiguous surfaces of said legs as clearly shown in Fig. 8 of the drawings.

Fastening elements passing through the openings in wings 14 and into suitable registering openings formed in the legs, securely retain the anchorage in permanent position. The lower surface of the anchoring piece 13 is in the plane of those of the legs 1 and 2 so that it will not tend to elevate the same. The outer surface of the anchorage 13 is inclined so that it may underlie the cushion of the head bank as will be understood without further discussion.

The inner longitudinal edges of the legs 1 and 2 respectively are beveled as at 14' and provided with rubber cushions 15 which are triangular in cross section. The extremities of the cushions 15 are beveled as at 16 so that the cushions at one extremity will miter, and at the other extremity form a continuation of the side bank cushions as shown in Fig. 2.

In order that the frame 2' may be locked in position, the beveled extremities 4 of the respective legs are provided with the channels 17 wherein, when the extremities 4 are disposed contiguous the cushions of the side banks C, they will coöperate with the latter to form a seat for the reception of a locking pin 18 which, when positioned, performs the function of a wedge, wherein it is absolutely impossible to dislodge the frame, and in this connection it is of course to be understood that that portion of the wedge which contacts with the cushions of the side bank, is beveled so as to conform with the inclination of the side banks C of the table.

Each of the locking pins 18 is provided with an enlarged head 18' having therein a notch 19 to accommodate the edges of the respective legs and permit the pins to be readily positioned in their seats. Inasmuch as these pins are used on opposite banks it is of course obvious that the beveled surfaces of the same are inverse, thus it would be impossible to transpose the respective pins as

will be readily understood without further discussion.

Each of the legs 1 and 2 of the frame has formed in the central portion of its upper surface, a longitudinally extending channel 19' for a purpose to be hereinafter set forth. Also there is formed in the under side of each of the legs adjacent the lower edge of the beveled portion thereof a channel 20.

To protect the cushions of the respective legs and partially cover the outer surfaces of the latter, a felt covering is provided for each of the same. This felt covering has one edge situated in the channel 20 formed adjacent the beveled edge of each of said legs, wherein it is fixed by the locking strip 23 which is positioned in said channel and maintained therein by suitable fastening elements. The other edge of the material is positioned in the channel 19' and maintained therein by means of a locking strip 24 which is secured to the leg by suitable fastening elements.

In operation, when it is desired to equip a pool or billiard table for use in connection with the game hereinbefore referred to, the frame 2' is disposed upon the bed of the pool table with the beveled portion of the metallic anchorage disposed in underlying relation with respect to the head bank D. The locking pins 18 are properly positioned in their respective seats, thus locking the frame in operative position. Miniature ten pins 25 are next disposed in the usual order at a predetermined point adjacent the leg 1 of the frame. After positioning the ten pins as desired a ball of the usual pool variety is positioned at a predetermined point adjacent the other end of the table and projected down the same by means of a cue into contact with the cushion on leg 2. Upon striking the latter, it will be deflected to the leg 1 from whence it will rebound to the pins 25 upsetting more or less of the same, dependent on the accuracy with which the ball was projected against the cushion. Each player may be allowed three shots and the counts determined by the number of pins displaced, as in the ordinary game of duck pins or ten pins.

From the above description it will be obvious that we have designed an attachment which will enable any pool or billiard table to be readily equipped and used in connection with the game aforesaid without in any way interfering with the table or preventing the same from being immediately used for pool or billiards as desired.

Although in the foregoing we have described certain elements as best adapted to perform the functions allotted to them, nevertheless it is to be understood that various changes in form, proportion, and in the minor details of construction may be resorted to within the scope of the appended

claims without departing from the spirit or sacrificing any of the principles of the invention.

We claim as our invention:—

5. 1. In a device of the character described, the combination with a game table having side banks, of an angular frame disposed upon said table intermediate the latter, a cushioning member disposed upon the inner 70 longitudinal edges of said frame and forming a continuation of those on said side banks, and means for locking said frame in operative position, substantially as and for the purpose set forth.
10. 2. In a device of the character described, the combination with a game table having side banks, of an angular frame disposed upon said table intermediate the latter, a cushioning member disposed upon the inner 80 longitudinal edges of said frame and forming a continuation of those on said side banks, and means for locking the free extremities of said angular frame to the side banks substantially as and for the purpose 85 set forth.
15. 3. In a device of the character described, the combination with a game table having side banks, of an angular frame disposed at one end of the table intermediate said 90 banks, the free extremities of said frame being disposed in mitering relation with respect to said side banks, a cushioning member carried by said frame and forming a continuation of the cushions on said side 95 banks, and means for locking said frame in operative position, substantially as and for the purpose set forth.
20. 4. In a device of the character described, the combination with a game table having side banks, of an angular frame disposed upon the table intermediate said banks, said frame having a longitudinally extending opening formed in the extremities thereof, and the latter disposed in mitering relation 100 with respect to the side banks, a cushion disposed on the inner longitudinal edge of said frame and forming a continuation of the cushions on said side banks, and a key positioned in the respective channels in the extremities of said frame, whereby to lock the latter in adjusted position, substantially as and for the purpose set forth. 110
25. 5. In a device of the character described, the combination with a game table having side and head banks, and an angular frame disposed upon one end of the table with its vertex disposed contiguous said side bank and coincident with the longitudinal axis of said table, the free ends of said frame being 120 situated in mitering relation with respect to the side banks, a cushion carried by said frame and forming a continuation of those on said side banks, substantially as and for the purpose set forth.
30. 6. In a device of the character described, 125 the combination with a game table having side and head banks, of a pair of members disposed in divergent relation intermediate said banks, cushions disposed upon the inner longitudinal edges of said members, and forming a continuation of those on said side banks, locking plates in connection with the meeting ends of said members to maintain the same in fixed relation, the free ends of said members being disposed in mitering relation with respect to said side banks and having therein a longitudinally extending channel, a locking pin disposed in the channels of the respective extremities whereby to retain the latter in fixed position, and a clamping element secured to and overlying the meeting edges of said members, said element being disposed contiguous said head bank substantially as and for the purpose set forth. 130
7. In a device of the character described, the combination with a game table having side and head banks, of a pair of cushioning members disposed in divergent relation intermediate said side banks, said cushioning members having their meeting extremities 75 disposed contiguous said head banks, angular locking plates mounted upon said members adjacent the meeting ends thereof, the free ends of said members being disposed in mitering relation with respect to said banks, 85 and means in connection with the free ends of said members for maintaining said members in operative position, substantially as and for the purpose set forth.
8. In a device of the character described, the combination with a game table having side and head banks, of a pair of members disposed in divergent relation upon one end of said table intermediate said banks, cushions disposed upon the inner longitudinal 95 edges of said members, and forming a continuation of those on said side banks, locking plates in connection with the meeting ends of said members to maintain the same in fixed relation, the free ends of said members being disposed in mitering relation with respect to said side banks and having therein a longitudinally extending channel, a locking pin disposed in the channels of the respective extremities whereby to retain the latter in fixed position, and a clamping element secured to and overlying the meeting edges of said members, said element being disposed contiguous said head bank substantially as and for the purpose set forth. 100
9. In a device of the character described, the combination with a game table having side and head banks, of a pair of members disposed in divergent relation upon one end of said table intermediate said banks, cushions disposed upon the inner longitudinal edges of said members and forming a continuation of those on said side banks, locking plates in connection with the meeting ends of said members to maintain the same 115 in fixed relation, the free ends of said members being disposed in mitering relation with respect to said side banks and having therein a longitudinally extending channel, a locking pin disposed in the channels of the respective extremities whereby to retain the latter in fixed position, and a clamping element carried by said members and having therein an angular opening to receive the meeting edges thereof, said element being 120
10. 6. In a device of the character described, 125 the combination with a game table having side and head banks, of a pair of members disposed in divergent relation intermediate said banks, cushions disposed upon the inner longitudinal edges of said members and forming a continuation of those on said side banks, locking plates in connection with the meeting ends of said members to maintain the same in fixed relation, the free ends of said members being disposed in mitering relation with respect to said side banks and having therein a longitudinally extending channel, a locking pin disposed in the channels of the respective extremities whereby to retain the latter in fixed position, and a clamping element carried by said members and having therein an angular opening to receive the meeting edges thereof, said element being 130

adapted to underlie the cushions of said head banks, substantially as and for the purpose set forth.

10. In a device of the character described, 5 the combination with a game table having side and head banks, of a pair of members disposed in divergent relation upon one end of said table intermediate said banks, cushions disposed upon the inner longitudinal edges of said members and forming a continuation of those on said side banks, locking plates in connection with the meeting ends of said members to maintain the same in fixed relation, the free ends of said members being disposed in mitering relation with respect to said side banks and having therein a longitudinally extending channel, a locking pin disposed in the channels of the respective extremities whereby to retain 20 the latter in fixed position, a clamping element carried by said members and having therein an annular opening to receive the meeting edges thereof, said element being adapted to underlie the cushions of said head bank, a protecting medium for the cushions of the respective members, and means in conjunction with the latter for clamping the edges of said protecting medium substantially as and for the purpose 25 set forth.

11. An attachment for a game table having side and head banks comprising a V-shaped frame having cushioning elements on its inner longitudinal edges, and means 35 at its vertex and at its extremities for detachably clamping said frame to said table, substantially as and for the purpose set forth.

12. An attachment for a game table having side and head banks, comprising a V- 40

shaped frame having cushioning elements on its inner longitudinal edges, and means at its vertex and at its extremities for detachably clamping the same to the head and side banks of the table respectively, 45 substantially as and for the purpose set forth.

13. An attachment for a game table having side and head banks, comprising a V-shaped frame having cushioning elements 50 on its inner longitudinal edges, means for detachably clamping the vertex of said frame to the head bank of the table, and wedge members for operating in channels in the extremities of said frame for detachably clamping the same to the side banks of the table, substantially as and for the purpose 55 set forth.

14. An attachment for a game table having undercut side and head banks, comprising 60 a V-shaped frame having cushioning elements on its inner longitudinal edges, means for detachably clamping the extremities of said frame to the side banks of the table, and a clamping element carried by the 65 vertex of said frame, said element having an outwardly extending nose adapted for engagement with the undercut head bank of the table for detachably clamping the vertex of the frame thereto, substantially 70 as and for the purpose set forth.

In testimony whereof we have hereunto set our hands in presence of two subscribing witnesses.

JOSEPH MASON.
WILLIAM J. BEATTIE.
